UNITED STATES PATENT OFFICE

JAMES J. LAWLER, OF MOUNT VERNON, NEW YORK

AUTOMATIC THERMOSTATIC RADIATOR VALVE

Application filed September 21, 1931. Serial No. 564,121.

This invention relates to certain new and useful improvements in automatic thermostatic radiator valves.

The primary object of the invention is to provide an automatic thermostatic radiator valve wherein a valve casing contains a valve seat with a manually operable valve engageable with one side thereof and a thermostatically operated valve engageable with the other side of the valve casing, may be controlled either manually or thermostatically.

A further object of the invention is to provide a radiator valve of the foregoing character wherein a ring or annulus forming a part of the valve casing and constructed to contain an expansible fluid, has an expansible tube in communication therewith and directly engaged with the thermostatically operative valve to effect automatic operation of said valve in controlling the opening and closing movements thereof, the expansible fluid being rendered more sensitive by the provision of a tubular cross arm extending between opposite sides of the ring or annulus and located in the valve casing in the path of flow of the heating medium.

With the above and other objects in view that will become apparent as the nature of the invention is better understood, the same consists of the novel construction, combination and arrangements of parts to be herein-after more fully described and then claimed.

In the accompanying drawing, forming a part of the application and to which reference is had by like characters designating corresponding parts throughout the several views:—

Figure 1 is a vertical longitudinal sectional view of an automatic thermostatic radiator valve constructed in accordance with the present invention, and showing the manual and thermostatically operated valves separately engageable with opposite sides of a valve seat, and

Figure 2 is a cross sectional view taken on lines 2—2 of Figure 1, showing the thermostatic ring or annulus and the tubular connecting web traversing the valve casing.

Referring more in detail to the accompanying drawing, there is illustrated an automatic

thermostatic radiator valve constructed for the manual and thermostatic control of the flow of heating medium therethrough, the valve comprising a casing 5 having a side outlet nipple 6 to which a connector 7 is attached by the nut 8, the connector 7 being adapted for attachment to a radiator or other heating element. The lower open end of the valve casing 5 has a fitting 9 engaged therewith as by a threaded connection and the fitting 9 is adapted to be placed into communication with the source of supply of a heating medium. A transverse web 10 is arranged interiorly of the valve casing 5 and forms an integral part of the wall structure thereof and is disposed below, the outlet 6^a through the nipple 6, the web having a central opening therein defining a valve passage with an oppositely extending annular flange surrounding the opening in the web to provide upper and lower valve seats 11 and 12 respectively.

The valve seat 11 is adapted to be engaged by a manually operated valve for shutting off the flow of the heating medium through the valve casing, this valve comprising a valve stem 13 threaded through a bushing 14 mounted in the upper end of the valve casing 5 and operated by the handle 15. The lower end of the valve stem 13 has a swivel connection 16 with a valve 17 that is constructed as illustrated with a removable and renewable disc member or washer to compensate for wear.

The thermostatically operated valve that is engageable with the valve seat 12 is associated with the lower end fitting 9, the thermostatic device comprising a tubular ring annulus 18 cast integral with the fitting 9 and surrounding the same, a tubular cross web 19 extending between opposite sides of ring or annulus as illustrated with the intermediate portion of the tubular web traversing the fitting 9 to be disposed in the path of flow of the heating medium so that expansible fluid within the annulus and web is rendered more sensitive to varying heat conditions. The ring or annulus is charged with expansible fluid by means of tubular nipples that are closed by screw plugs 20.

A central opening is formed in the upper wall of the tubular web 19 within the fitting 9 and said opening is surrounded by an up-standing expansible tube 21 that has its lower 5 open end soldered, welded or otherwise secured to the walls of the web opening to place the expansible tube in communication with the web and annulus. A cylindrical plug core 22 is disposed within the expansible tube 10 21 with the upper end thereof anchored to the closed upper end of the expansible tube, while the lower end of the plug core extends downwardly through the opening in the upper wall of the web 19, the plug core moving 15 in wiping contact with the wall of the web opening, the core having a longitudinally extending facial groove 23 to permit the flow of expansible fluid from the annulus and web into the expansible tube 21. A valve 20 24 is carried by the upper end of the expansible tube 21 and is adapted to be moved into engagement with the valve seat 12, and to eliminate vibration of the valve 24 and to insure proper operation of the thermostatic 25 devices associated therewith, there is provided a coil spring 25 interposed between the valves 17 and 24.

From the above detailed description of the device, it is believed that the construction 30 and operation thereof would at once be apparent, it being noted that the flow of heating medium through the valve casing may be shut off when desired by the manually operated valve 17 that is engageable with the 35 valve seat 11. The automatic closing of the valve is accomplished by the thermostatically operated valve 24 that moves into engagement with the seat 12, the atmosphere or air surrounding the radiator valve flowing in 40 contact with all surfaces of the ring or annulus 18 while the heating medium flows in contact with the web 19 to render the operation of the thermostatic devices more sensitive. The expansible fluid causing expansion 45 and contraction of the expansible tube 21 and corresponding movement of the valve 24 toward and away from its seat 12.

While there is herein shown and described the preferred embodiment of the invention, 50 it is to be understood that minor changes may be made therein, such as will fall within the scope of the invention as claimed.

What I claim as new is:

1. In an automatic thermostatic radiator 55 valve, valve casing, a double valve seat therein, and manual and thermostatically operated valves respectively engageable with the valve seats, the thermostatic valve comprising an expansible tube and an annulus in 60 communication with the tube, and surrounding the valve casing and containing an expansible fluid, and a tubular web extending between sides of the annulus and transversing 65 the valve casing in the path of flow of the heating medium.

2. In an automatic thermostatic radiator valve, valve casing, a double valve seat therein, and manual and thermostatically operated valves respectively engaged with the valve seats, the thermostatic valve comprising an expansible fluid containing an annulus formed integral with the valve casing, and an expansible tube in communication with the annulus and carrying the thermostatically operated valve, and a tubular web 70 extending between sides of the annulus and transversing the valve casing in the path of flow of the heating medium.

3. In an automatic thermostatic radiator valve, valve casing, a double valve seat therein, and manual and thermostatically operated valves respectively engaged with the valve seats, the thermostatic valve comprising an expansible fluid containing annulus 80 formed integral with the valve casing and surrounding the casing, and an expansible tube in communication with the annulus and carrying the thermostatically operated valve, and a tubular web 85 extending between sides of the annulus and transversing the valve casing in the path of flow of the heating medium.

In testimony whereof I affix my signature.

JAMES J. LAWLER.
